UNITED STATES PATENT OFFICE

121,214

DESIGN FOR A BOAT

Albert Saunders, Barbourville, Ky.

Application April 20, 1940, Serial No. 91,797

Term of patent 7 years

To all whom it may concern:

Be it known that I, Albert Saunders, a citizen of the United States, residing at Barbourville, in the county of Knox and State of Kentucky, have invented a new, original, and ornamental Design for a Boat, of which the following is a specification, reference being had to the accompanying drawing, forming part thereof.

I claim:

The ornamental design for a boat, as shown.

ALBERT SAUNDERS,
